UNITED STATES PATENT OFFICE.

FRED JOSEPH MOSER, OF NORTH CLARENDON, PENNSYLVANIA.

CLAMP.

SPECIFICATION forming part of Letters Patent No. 368,104, dated August 9, 1887.

Application filed April 26, 1887. Serial No. 236,222. (No model.)

To all whom it may concern:

Be it known that I, FRED JOSEPH MOSER, a citizen of the United States, residing at North Clarendon, in the county of Warren and 5 State of Pennsylvania, have invented new and useful Improvements in Clamps, of which the following is a specification.

My invention relates to an improvement in clamps for raising and lowering oil-well tubes; 10 and it consists in the peculiar construction and combination of devices, that will be more fully set forth hereinafter, and particularly pointed out in the claims.

In the drawings, Figure 1 is a perspective 15 view of a clamp embodying my improvements, showing the jaws of the same open. Fig. 2 is a similar view showing the jaws closed. Fig. 3 is a vertical transverse sectional view, taken on the line $\alpha\alpha$ of Fig. 1.

20 A B represent a pair of jaws, which are hinged together at their outer sides by means of a vertical pin or bolt, C, which extends through vertical aligned openings made in circular ears D and E, which project from the outer sides of the jaws A and B, respectively. The said jaws are provided with outwardly-extending semi-cylindrical curved portions F and G, the inner concave sides of which are arranged opposite to each other, and when the 25 jaws are closed form a cylindrical opening adapted to receive the oil-well tubing to be raised or lowered. From the outer sides of the semi-cylindrical curved portions of the jaws project eyes H, which are formed integrally with the jaws, and engage long links I, of suitable size and thickness, which are adapted to be hooked to the snatch-block of the hoisting tackle. (Not shown.)

The upper side of the curved portion G of 30 the jaw B is recessed or cut away, as at K, and on the said recess or cut-away portion rests a semicircular latch, L, the outer end of which is provided with a circular lug or ear, M, which is pivoted on the bolt C between the upper ear D of the jaw A and the upper ear E of the jaw B. The thickness of the said ear or lug M is not equal to the width of the space between the said ears D and E, and the opening in the said ear or lug M is larger than the diameter of the bolt C, and thereby the latch L is adapted to have its outer end raised and lowered for the purpose to be hereinafter de-

scribed. The free end of the latch is provided on its under side with a depending hook or barb, N, the front under side of which is 55 inclined.

In the upper edge of the jaw A is a vertical rectangular notch or recess, O, adapted to receive the free end of the latch when the jaws close together on the tubing, so as to guide 60 the lower side of the free end of the latch over the recess O, and cause it to drop on the outer side of the jaw A when the latter comes in contact with the jaw B, and thereby cause the depending offset or hook N of the latch to lock 65 the jaws A and B together. The flange or head which projects from the outer side of the tubing rests on the latch L, as shown in Fig. 3, and thereby the weight of the said tubing keeps the latch closed and prevents it from accidentally releasing the jaws. 70

Each jaw A and B is provided at its free side with a projecting arm, P and R, respectively. On the inner side of the arm P is a recess or groove, S, and on the inner side of the arm R is a corresponding projecting offset or tongue, T, which is adapted to enter the recess S when the jaws are closed together, and thereby prevent the hinged ears of the said jaws from working on the pintle or bolt C, 80 and thereby subjecting the latter to strain. 75

In operation the jaws A B are moved to clamp the tube, in which position they are rigidly held by the latch L, the curved face of the hooked end of which contacts with the 85 jaw A, and causes the latch to be lifted until said jaw A arrives in position, when the hooked end N takes over the recessed portion of said jaw. When the arms P R are in the position shown in Fig. 2, they form between 90 them a horizontal socket, in which may be inserted the end of a bar to form a handle for manipulating the clamp.

Having thus described my invention, I claim—

1. In a clamp for raising and lowering oil-well tubes, the combination of the jaws A and B, hinged together and adapted to engage and receive the opposite sides of the tube, one of the said jaws being recessed or cut away on its upper edge, and the pivoted latch L, fitting in the said recessed or cut-away portion, and having the hook or catch N at its free end adapted to engage the upper edge of the op- 95 100

posite jaw when the jaws close together, substantially as described.

2. The combination, in a clamp for oil-wells, of the jaws A B, pivoted together, and the horizontally-pivoted gravitating latch, having the hooked end N, curved on its end face, substantially as set forth.

In testimony that I claim the foregoing as my own I have hereto affixed my signature in presence of two witnesses.

FRED JOSEPH MOSER.

Witnesses:

HENRY L. HERSHFIELD,
JAMES DONALDSON.
